Inventor:
Henry G. Lewis,
By Chas. N. Butler
Attorney.

UNITED STATES PATENT OFFICE.

HENRY G. LEWIS, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

SHADE AND REFLECTOR.

1,322,910.

Specification of Letters Patent.

Patented Nov. 25, 1919.

Application filed June 9, 1917. Serial No. 173,708.

To all whom it may concern:

Be it known that I, HENRY G. LEWIS, a citizen of the United States, residing in the city of Philadelphia, county of Philadelphia, and State of Pennsylvania, have invented Improved Shades and Reflectors, of which the following is a specification.

My invention is an improved device designed for shading and diffusing light and throwing a beam upon an object which it is desired to illuminate highly.

A use of my improved device is found in lighting street cars, for example, where it is desirable to shade and diffuse the light from lamps for the purpose of obtaining satisfactory general illumination and, at the same time, to throw beams from particular lamps upon objects, as registers, which it is desirable to illuminate so that they can be read with greater facility.

The characteristic features of my invention are disclosed more specifically in the following description and the accompanying drawings in illustration thereof.

25 In the drawings, Figure 1 is a top plan view of a device embodying a form of my invention selected for the purpose of illustrating an application thereof; Fig. 2 is a side elevation of the device shown in Fig. 1 in combination with a lamp; and Fig. 3 is a side elevation of mechanism shown in Fig. 2 turned through an angle of 90 degrees and a dial disposed in the path of a beam of light reflected by the mechanism.

30 35 In the form of the invention here selected for the purpose of illustrating an application thereof, a glass shade and reflector of paraboloidal character in its general contour, is provided with a translucent or semi-transparent portion 1 and the transparent portion 2. The translucent character is imparted in any usual manner, as by enameling or frosting the glass by which it is desired to diffuse subdued light from the lamp 3, and the clear portion 2 preferably has the character adapted for permitting the passage without substantial obstruction of the direct and reflected light from the lamp to an object, such as the dial 4.

40 45 50 The device thus effects the desiderata of diffusing light from the lamp, subduing the direct rays in the line of vision of those

in the field of light, and throwing substantially unobstructed and unmodified direct and reflected light upon the object to be highly illuminated.

It is generally desirable that cars be equipped with lamps provided with reflectors on account of their much higher lighting efficiency, better diffusion, better appearance, and greater comfort to passengers. Many cars are provided with objects, such as destination signs and registers, which have been illuminated heretofore, more or less imperfectly, by bare lamps, and where the usual improved reflecting and diffusing fixtures were added the illumination of these objects was greatly reduced. This device effects the desired reflection and illumination of light not only without the imperfect illumination of signs and other objects used for visually conveying intelligence, but it is adapted for accentuating the illumination of such objects as signs by throwing direct and reflected light with substantial uniformity over the entire area to be read.

Having described my invention, I claim:

1. A parabolic shade and reflector expanding to an opening and having a transparent section and a translucent section adapted for reflecting light through said opening and said transparent section.

2. A glass shade and reflector of substantially paraboloidal contour having a transparent section and a translucent section adapted for diffusing subdued light and for reflecting a beam of light through said transparent section.

3. A glass shade and reflector having a relatively small transparent parabolic section and a comparatively large translucent parabolic section adapted for diffusing subdued light and for reflecting a beam of light through said transparent section.

4. A shade and reflector expanding to an opening and having a transparent parabolic section and a translucent section, said translucent parabolic section adapted to reflect light through said opening and said transparent section.

In testimony whereof, I have hereunto set my name this 4th day of June, 1917.

H. G. LEWIS.
